a corporation of Michigan

Application April 15, 1950, Serial No. 9,239

Term of patent 7 years

(Cl. D14—6)

To all whom it may concern:

Be it known that I, Carlton G. Koonter, a citizen of the United States, residing at Fairhaven, St. Clair County, Michigan, have invented a new, original, and ornamental Design for an Exhaust Pipe Extension or Similar Article for an Automobile, of which the following is a specification, reference being had to the accompanying drawing, forming a part thereof.

Fig. 1 is a perspective view of an exhaust pipe extension or similar article for an automobile, embodying my invention.

Fig. 2 is a plan view thereof.

The characteristic features of my design reside in the portions shown by means of full lines in the drawing.

I claim:

The ornamental design of an exhaust pipe extension or similar article for an automobile, substantially as shown and described.

CARLTON G. KOONTER.
